UNITED STATES PATENT OFFICE.

JOSEPH F. DREDGE AND JAMES BURKE, OF RACINE, WISCONSIN.

DESIGN FOR A RUB-IRON OR FENDER FOR VEHICLES.

SPECIFICATION forming part of Design No. 35,567, dated January 7, 1902.

Application filed November 23, 1901. Serial No. 83,489. Term of patent 3½ years.

To all whom it may concern:

Be it known that we, JOSEPH F. DREDGE and JAMES BURKE, citizens of the United States, residing at Racine, in the county of Racine and State of Wisconsin, have invented and produced a new and original Design for a Rub-Iron or Fender for Vehicles; and we do hereby declare the following to be a full, clear, and exact description of the invention, such as will enable others skilled in the art to which it appertains to make and use the same.

This invention has relation to a unique design for a rub-iron or fender for vehicles; and it consists of the novel configuration substantially as shown in the accompanying facsimile drawings, in which—

Figure 1 is a perspective view, and Fig. 2 a plan view.

The design consists, essentially, of a flat plate having its longitudinal edges 1 and 2 straight and relatively diverged from the end 3, which is straight and forms an obtuse angle with the edge 1 and an approximately right angle with the edge 2. The opposite end is 25 forked, the arms 3^a and 4 being separated by

a depression whose edge 5 is curved. The end of the arm 3^a is straight, as shown at 6, and about at a right angle to the edge 1, and the end 7 of the arm 4 is likewise straight and arranged about at a right angle to the edge 2. 30 Oblong openings 8 and 9 parallel the edge 1 and are located near thereto. An opening or space 10 is arranged close to and parallel with the edge 2 and has its inner edge curved and its outer edge straight. The edge portion 35 2 is round in end view and projects beyond opposite sides of the flat body, as indicated in Fig. 1.

Having thus described the invention, what is claimed as new is—

The design for a vehicle rub-iron, substantially as herein shown and described.

In testimony whereof we affix our signatures in presence of two witnesses.

JOSEPH F. DREDGE. [L. S.]
JAMES BURKE. [L. S.]
